US00D548804S

(12) **United States Design Patent** (10) Patent No.: **US D548,804 S**
D'Ambrosio et al. (45) Date of Patent: **** Aug. 14, 2007**

(54) **BUILDING BLOCK**

(76) Inventors: **Peter Carlo D'Ambrosio**, Marden Ash,
20 Eldorado Road, Cheltenham,
Gloucester, GL50 2PT (GB); **Roy
Austin Smith**, 17A Eldorado Road,
Cheltenham, Gloucester, GL50 2PU
(GB)

(**) Term: **14 Years**

(21) Appl. No.: **29/223,193**

(22) Filed: **Feb. 10, 2005**

(30) **Foreign Application Priority Data**

Aug. 20, 2004 (EM) 000217096

(51) LOC (8) Cl. **21-01**

(52) U.S. Cl. **D21/492**

(58) Field of Classification Search D21/483,
D21/484-485, 489-493, 500-505; D25/113-118;
446/85, 101-128, 69; 434/403

See application file for complete search history.

(57) **CLAIM**

The ornamental design for a building block, as shown and described.

DESCRIPTION

A portion of the disclosure of this patent, including appendices, may contain material which is subject to copyright protection. The copyright owner has no objection to the facsimile reproduction by anyone of the patent document or the patent disclosure, as it appears in the Patent and Trademark Office patent file or records, but otherwise reserves all copyright rights whatsoever.

FIG. 1 is a top plan view of the building block of the present invention; and,

FIG. 2 is a perspective view thereof.
